UNITED STATES PATENT OFFICE.

LUCIUS E. WHITON, OF NEW LONDON, CONNECTICUT.

CENTERING-MACHINE.

SPECIFICATION forming part of Letters Patent No. 698,608, dated April 29, 1902.

Application filed March 7, 1899. Serial No. 708,148. (No model.)

To all whom it may concern:

Be it known that I, LUCIUS E. WHITON, a citizen of the United States, residing at New London, in the county of New London, State 5 of Connecticut, have invented certain new and useful Improvements in Centering-Machines, of which the following is a full, clear, and exact description.

This invention is in machines for centering 10 shafting and the like rods of metal; and said invention has for its chief object the improvement of the means provided for holding and revolving the rods, to the end that the work may be performed more perfect and rapidly 15 than has been possible heretofore.

For the purpose of explaining the various 20 elements and operation of my improved centering-machine I have annexed hereto three sheets of drawings, to which reference is made, Figure 1 being an elevation, and Fig. 2 a plan view, of my said machine. Figs. 3 and 4 are end elevations of said machine as viewed, respectively, from the left-hand and right-hand ends of Fig. 1. Fig. 3 shows in elevation 25 the centering-chuck 52 and the manner in which its adjustable jaws support the revolving work while the same is being centered. Fig. 5 is an enlarged view of the work-holding chuck 42 and connected parts, 30 this view being taken on line 1 of Fig. 1 looking in the direction of the arrow; and Fig. 6 is a similar view looking in the opposite direction—that is to say, toward the head that supports the centering-tools. Fig. 7 illustrates 35 in central section the driving-pulley 27 and a train of gearing connected therewith, by means of which rotary motion is transferred to the chuck 42, as I shall explain in detail later. In Fig. 8 I have shown certain 40 of the gears of the said train, the pulley being indicated by the dotted circle surrounding said gears. Fig. 9 is a longitudinal central sectional view of the machine-bed and the work-holding chuck mounted thereon. 45 Said view also includes a portion of the said bed in elevation and a simple chuck provided thereon for supporting that end of the rod that is being centered. It should be understood that this last-named chuck does not 50 clamp the rod tightly during the centering operation, but is so adjusted that while it supports the rod end in proper position to be

operated upon by the drill the rod is free to rotate within said chuck. Per contra, the chuck 42 is so adjusted that it clamps the 55 rod tightly and when set in revolution imparts like motion to the rod. Fig. 10 is a sectional view taken on a vertical plane at a right angle to that of Fig. 9 and is provided to illustrate and emphasize a very important 60 feature of my improved machine, whereby the work-holding chuck 42 may be conveniently swung aside when it is desired to simply support a rod during the centering operation, but not to revolve said rod. Fig. 11 65 is a longitudinal central sectional view taken on line 10 of Fig. 10, showing the manner of mounting and hinging (upon a certain shaft 33) the chuck 42.

In the drawings, 20 indicates the machine-bed, mounted upon suitable legs and having formed on its upper face ways 21, upon which are mounted and held in alinement the drill-supporting mechanism and the chucks by means of which the rod that is to be centered 70 is held. The drill supporting and driving mechanism, which I will briefly describe, is in the main old, (being the subject of United States Patent No. 426,347, dated April 22, 1890,) the only improved feature in connection therewith being certain means for conveying rotary motion to the work-holding chuck at the opposite end of the machine. Said drill-supporting mechanism consists of a head 22, that is bored to receive a stud 23, on which 75 is loosely mounted a gear having two toothed steps 24 25 of different diameters, as is best seen in Figs. 7 and 8. This double gear is formed with an extended hub portion 26, on which is mounted a pulley 27, the said gear 80 and pulley being secured together and adapted to revolve as a single structure on the stud 23.

28 denotes a frame in which are mounted two spindles 29 30, the former of which is 85 adapted to receive a drill and the latter a countersinking-tool. These spindles are longitudinally movable in frame 28 and are adapted to be engaged and slid forward and backward by a gear 30², mounted upon a 90 short shaft 30³, which shaft is journaled in the head 22 and is provided with an operating-handle 30⁴ of lever form.

Referring now to Fig. 8, it will be seen that

the shank of spindle 29 has fixed thereon a gear 29' and that the shank of spindle 30 has fixed thereon a similar gear 30'. These gears 29' and 30' are not in the same vertical plane, 5 but are so located that the former meshes with gear 24 and the latter (30') meshes with the gear 25, already described.

The frame 28 has an extension 28', that is loosely mounted on the stud 23. (See Figs. 6 10 and 7.) The said frame 28 may thus be rocked on stud 23 to alternately move the drill and countersink into their operative positions—that is to say, immediately over the center of the stud—and for the purpose of limiting the 15 rocking movement of the frame 28 I provide in the head 22 adjustable stop-screws 31 and check-nuts 32. (See Fig. 6.) 28² denotes a handle attached to frame 28, by means of which the said frame may be conveniently 20 rocked whenever it is desired to shift the positions of the drill and countersink.

The driving mechanism of the head 22 thus far described is old, and it should be understood that I make no claim to it here.

25 I will now proceed to describe the peculiar train and arrangement of gearing by means of which rotary motion is transmitted to the work-holding chuck at the opposite end of the machine.

30 33 denotes a shaft located at the back of the machine and journaled at one end in an extension 22' of the head 22. The other end of said shaft is supported in an extension 34' of a slider 34, that is mounted on the ways 21.

35 Near the head extension 22' is a gear 35, that is fixed on the shaft 33. Journaled in the head 22 is a short shaft 36, (shown in dotted lines in Figs. 6 and 7 and in full lines in Fig. 8,) which shaft bears on its opposite ends

40 gears 36' 36², the former of which engages the same gear 24 that drives the "countersink-gear" 30'. (See Fig. 8.) Gear 36² engages a pinion-gear 37', mounted on a short shaft 37, and said gear 37' engages, in turn, the gear 35

45 on the shaft 33. A train of gearing, commencing with gear 25 on stud 26 and ending with gear 35 on shaft 33, is thus provided, and it will be obvious that when the pulley 27 is set in revolution like motion will be imparted to the shaft 33.

50 The shaft 37 has a long bearing in the frame 22 and is so arranged that it may be moved longitudinally in its said bearing in order that the gear 37' may be withdrawn 55 from its operative position in the train, as shown in dotted lines in Fig. 7, this result being sometimes desirable when it is not necessary to revolve shaft 33.

56 38 denotes a ball-shaped handle on the projecting end of shaft 37, by means of which the said shaft may be conveniently drawn forward when it is desired to throw the gears out of mesh, as I have just explained.

65 The connection between shaft 33 and the chuck-bearing slider 34 is peculiarly made and is best seen in Figs. 5, 10, and 11. It may be stated by way of explanation that

the slider 34 is adjustable on ways 21 and must therefore be freely movable along the said shaft 33 and that the connection between the slider and shaft also serves as a hinge, by means of which the work-holding chuck may be swung back out of the way, this feature being clearly illustrated in Fig. 10 of the drawings. Shaft 33 is formed with a 75 "key-seat" 33', that extends throughout the major part of its length, and loosely mounted on said shaft is a sleeve 39, in which is a spline 40, that coacts with the described key-seat. Around the sleeve 39 is a somewhat 80 shorter sleeve 41, on which are located the two slider extension portions 34', and between these slider portions is an extension 42' of the work-holding-chuck bearing 42². To hold the several hinge, sleeve, and spline elements in their properly-assembled positions, a collar 39' and a gear 39² are fixedly mounted upon the projecting ends of the sleeve 39. Gear 39² meshes with a large gear 42², formed as a part of or rigidly attached to the work-holding chuck 42, and it will now be understood that when the machine is in operation the rotation of shaft 33 will impart a slow rotary movement to the chuck 42 and to the rod clamped by said chuck, the direction of rotation of said chuck and shaft being preferably, but not necessarily, the opposite of that imparted to the drill and countersink. The end of the shaft to be centered projects through and is loosely supported by the adjustable 100 jaws of the stationary centering-chuck 52, as shown clearly in Figs. 1 and 3^a. When thus supported and caused to revolve by the chuck 42 in the manner described, the center produced by advancing the drilling and counter-sinking tools will be located with perfect accuracy in relation to the exterior surface of the revolving shaft. It is thus possible by means of my improved machine to accurately 105 center shafts of which the exterior surface has been previously finished, and thus enable short portions of such shafts to be afterward turned in the lathe if necessary in fitting other machine parts. It has heretofore been practically impossible to produce sufficiently accurate centers in such previously-finished shafts when held stationary in ordinary centering-machines.

I have already explained that the chuck 42 may be swung back out of the way, and when 120 in this position, as shown in Fig. 10, ordinary unfinished bars may be firmly held and centered in the chuck 52 with sufficient accuracy for the usual requirement of turning the exterior surface. My improved machine is therefore adapted both for centering work of which the exterior surface is afterward to be finished with relation to the centers so produced and for locating the centers in accurate relation with a previously-finished exterior surface, 125 as may be required. When the revolving chuck 42 is returned to its operative position, it rests upon ways 34², formed on the upper face of the slider 34, thus insuring the perfect 130

alinement of the chuck, the slider 34, and the machine-bed 20. When the work-holding chuck is thus seated on the slider 34, it is securely fastened and made a practically rigid part of said slider by means of a chain 43, a bolt 44, and a binding-nut 45, as will be best understood by reference to Figs. 9 and 10. The bolt 44 extends downward through a central opening in the slider 34 and through a longitudinal slot 20' in the machine-bed, and the upper end of the bolt is connected with the lower part of the chuck by the chain 43, the latter being of such length that when the chuck is folded down upon the slider it (the chain) reaches nearly to the bottom of the machine-bed. The said bolt is supported in part by a bracket 46, that is held in vertical alinement with the slider-opening by a screw 47, extending downward from the said slider, which also serves to clamp the slider 34 in the required position upon the bed. Near its upper end the bolt 44 is somewhat enlarged and threaded, as at 44', and the lower or exposed end of said bolt has fixed thereon a nut 48, that serves to prevent the nut 45 from leaving the bolt when the said nut 45 is unscrewed from the threaded part 44' of the bolt. When the chuck is folded down upon the slider, the chain and connected bolt pass downward by gravity through the slider-opening and nearly through the opening in the bracket 46, as seen in Fig. 9. The nut 45 is then slipped upward on the bolt 44 until it engages the threaded part 44' and is finally screwed home on said threaded part until it abuts the lower end of bracket 46, and thus makes taut the chain 43, clamping the chuck 42, slider 34, and bed 20 together. When it is again desired to swing the chuck open, as in Fig. 10, it is only necessary to unscrew the nut 45 from the threaded part 44', when said nut immediately slips down the bolt until checked by the stop-nut 48. The chuck may then be swung open, drawing upward with it the chain and bolt until the nut 45 abuts the lower end of bracket 46. When the machine is to be used with the chuck 42 thus removed from its operative position, a simple support for the rod to be centered is ordinarily required, and this I provide in the form of a vertically-adjustable rod 49, located in an opening in the slider 34 just in the rear of the chuck 42, the upper or head portion of said rod being formed with a V-shaped opening 50. This rod 49 may be clamped in desired position after adjustment by a screw 51.

I have referred to the entire hinged element 42 as the "work-holding chuck," for the reason that when its several parts are assembled it is practically a single structure. For convenience of manufacture it is preferable that it be built up of several parts, substantially as shown; but it is not imperative that it be so constructed. It is only necessary that the chuck proper be capable of rotation, and this is accomplished in this present in-

stance by providing on the chuck a tubular extension 42⁵, that is fitted to revolve within a shell or bearing 42³, which latter is an integral part of the hinge 42'. The chuck proper I have shown as an ordinary scroll-chuck; but any other form of self-centering chuck would serve the purpose equally well. When operating upon a long shaft or rod, the work-holding chuck 42 is moved back to the extreme end of the machine-bed, thus separating the two shaft-supports—to wit, the chucks 42 and 50—as far as possible.

When my described machine is about to be used, the shaft *a* to be centered is first passed through the chucks 42 52, as seen in Fig. 1. The two chucks are then adjusted, so that the shaft is clamped firmly by the chuck 42, but is simply centered and loosely supported by the chuck 52. The pulley 27 is then set in revolution, and through the described train of gearing, shaft 33, and gears 39² 42² the work-holding chuck 42 is caused to rotate slowly. The lever 30⁴ is then moved to force the drill into cutting engagement with the shaft *a*, and so soon as the hole is deep enough the drill is withdrawn, the handle 28² is grasped, and the frame 28 is rocked to bring the countersink into the position last occupied by the drill—that is to say, into coincidence with the hole drilled in the end of the shaft. The countersink is then forced forward and the hole is countersunk to the proper depth, the machine is stopped, and the shaft removed, the several described operations being performed quickly and accurately and without the aid of a specially-skilled operator.

Having described my invention, I claim—

1. In combination, drilling mechanism, consisting of a laterally-movable head carrying two or more revolving and sliding spindles, means substantially as specified for sliding said spindles, means for supporting the rod to be centered consisting of a fixed chuck and a revoluble chuck, a swinging support for said revoluble chuck as set forth, and mechanism for simultaneously revolving the said spindles and the said rod.

2. In combination, a machine-bed, a slider mounted thereon, a work-holding chuck hinged to said slider, a bolt in the slider having an enlarged threaded portion and a reduced body portion, a chain connecting the bolt and chuck, and a nut adapted to coact with the said threaded portion of the bolt, for the purpose specified.

3. In combination, a machine-bed, a slider mounted on the said bed and formed with lateral extensions 34', sleeves 39 41 located within said extensions, a splined shaft supported within and by the sleeve 39, a work-holding chuck mounted on the slider and formed with an extension 42' that is hinged on the sleeve 41 substantially as specified.

4. In combination, a machine-bed, a slider mounted on the said bed and formed with one or more lateral extensions 34', a sleeve 39 pro-

vided with gear 39² and key 40 located within said lateral extension, a splined shaft supported within and by the sleeve 39, a work-holding-chuck bearing 42³ mounted on the 5 slider and formed with an extension 42' that is hinged on the said sleeve, and a work-holding chuck revolubly mounted within the chuck-bearing 42³ and provided with a gear

42² which is adapted to coact with the gear 39² substantially as specified.

Signed at New London, Connecticut, this 28th day of February, 1899.

LUCIUS E. WHITON.
